UNITED STATES PATENT OFFICE.

HENRY GOWER HOSE, OF BROOKLYN, NEW YORK.

CHANGEABLE-FEATURE FIGURE TOY.

Application filed January 15, 1926. Serial No. 81,427.

My invention relates to toys or playthings for children, and specifically to that form of such devices in which a piece of cardboard or the like is printed in such a way as to simulate the features of a face, and in which devices are provided for changing the expression of one or more of such features and thereby the expression of the whole face, and more specifically still the invention relates, in certain embodiments thereof, to a representation on cardboard or the like of a face, with certain of the features thereof delineated thereon, provided with apertures formed in such face behind which apertures are pivotally mounted rotatable disks having features impressed thereon which are adapted to be successively and independently brought into register with their respective openings.

20 The object of the invention is to provide a simple and easily operated toy of the character described, which shall be capable of economical manufacture.

The invention consists in the novel construction, arrangement and combination of various devices, elements and parts, as set forth in the claims hereof, certain embodiments of the same being illustrated in the accompanying drawings and described in this specification.

In the accompanying drawings,

Fig. 1 is a front view of a device of the character described, showing one modification of my invention;

35 Fig. 2 is a transverse vertical section along the line 2—2 of Fig. 1;

Fig. 3 is a front view of a modified form of the invention; and

40 Fig. 4 is a transverse vertical section along the line 4—4 of Fig. 3.

In carrying my invention into effect according to the embodiment thereof which I have illustrated in Figs. 1 and 2 of the accompanying drawings, I provide a piece of cardboard or the like 11, upon which are impressed certain features, such as a nose 12, ears 13, and the like. A pair of openings 14, 14, are provided approximately in the location of the eyes of such a face, and 50 an opening 15 approximately in the position of the mouth.

Pivotally secured to the member 11 at 16 are a pair of members 17, 17, the main portion of which members 17 lies behind the

member 11 but a slight portion of which projects laterally beyond the edge of the member 11.

Pivots secured to the member 11 at 18 is a member 19, the main portion of which lies behind the member 11, but a slight portion of which projects downwards beyond the lower edge of the member 11.

Upon the members 17 may be printed features, as 20, and upon the member 19 may be printed features as 21.

The operation of this embodiment of my invention will be well understood from what has been above said. It is obvious that by merely rotating one or more of the disks 17 and 19, amusing variations in the expression 70 of the face may be produced.

In carrying my invention into effect in the embodiment shown in Figs. 3 and 4 of the accompanying drawings, I provide a face member 31 analogous to the member 11 shown in Figs. 1 and 2. This face member is provided with eye openings 32 and a mouth opening 33, as well as such other features as may be desired to be delineated thereon. Pivots secured to the member 31 at 34 is a rotatable member 35, the main portion of which member 35 lies behind the member 31 but a slight portion of which projects laterally beyond the edge of the member 31. Upon the member 35 may be 85 printed features, as 36 and 37.

The operation of this embodiment of my invention is entirely analogous to that of the previously described embodiment, with the exception that in this case only one disk 90 is rotated.

The advantages of my invention will be obvious from what has been above said with regard to its construction and operation.

I do not limit myself to the exact form of construction which has been above described and is herewith illustrated, as it is obvious that various departures therefrom can be made without leaving the spirit and scope of my invention. For instance, it may sometimes be preferred to provide the device with a handle, so that the same, in addition to its amusing expression-changing operation, may also be used as a fan.

Having thus described my invention, what I claim as new and desire to secure by Letters Patent is as follows:

In a device of the character described, the

combination with a flat face-shaped member having facial features and apertures; of a flat circular member secured to said first-named member and adapted to rotate in a plane parallel thereto having other facial features which are adapted to be seen through said apertures: whereby the fea-

tures upon said members taken together represent a face and the rotation of said members with reference to each other ¹⁰ changes the expression on said face.

In witness whereof I have hereunto signed my name this 13th day of January, 1926.

HENRY GOWER HOSE.
